UNITED STATES PATENT OFFICE.

ERNEST P. WARNER, OF CHICAGO, ILLINOIS.

DESIGN FOR AN ELECTRIC-LAMP POST.

SPECIFICATION forming part of Design No. 20,688, dated April 21, 1891.

Application filed August 11, 1890. Serial No. 361,739. Term of patent 14 years.

To all whom it may concern:

Be it known that I, ERNEST P. WARNER, a citizen of the United States, residing at Chicago, in the county of Cook and State of Illinois, have invented and produced a new and original Design for Electric-Lamp Posts, of which the following is a full, clear, concise, and exact description, reference being had to the accompanying drawing, forming a part of this specification.

In the drawing I have shown a perspective view of a lamp-post embodying my design.

The leading feature of my design consists in the form of the base. This base is provided with faces having the appearance of parabolic curves. These faces are ornamented each at its upper portion with a depression having the appearance of a panel, and below these upper panels are provided other depressions relieved by central ornaments or rosettes. This base is encircled by bands, one at the upper portion thereof. Another band is placed at or near the central portion of the base, while a third band is placed below the ornamented paneling. The foot of the base is circular and is provided with niches or semicircular depressions below the lower band. The mast or column rising above

the base is provided with ornamental steps on opposite sides thereof. The cross-arm is placed at the top of this column and braced with ornamental brackets. The lamp-*hood* rises above this column. Thus in the drawing the foot *a* is circular, the depressions or niches *b* are semicircular, the ornamented panels are placed between bands *c d*, and the upper portion of the base is ornamented with panels *e* and a band *f*. The parabolically-curved faces, ornamented as described, have been found very acceptable and pleasing. The mast or column *g*, rising above the base, is provided with steps ornamented as shown and with a ladder-rest or cross-arm above an ornamental bracket.

Having thus described my invention, I claim as new and desire to secure by Letters Patent—

The design for an electric-lamp post, as described and shown.

In witness whereof I hereunto subscribe my name this 5th day of August, A. D. 1890.

ERNEST P. WARNER.
